UNITED STATES PATENT OFFICE

2,552,624

DOOR CLOSING APPARATUS, INCLUDING
ELECTRICALLY DRIVEN GEAR PUMP
AND OSCILLATING VANE MOTOR HY-
DRAULIC TRANSMISSION

Frederick W. Enzenbacher, Longmeadow, Mass.

Application September 13, 1948, Serial No. 49,059

3 Claims. (Cl. 60—52)

1

This invention relates to improvements in door closing apparatus including electrically driven gear pump and oscillating vane motor hydraulic transmission, or the like, and is directed more particularly to improvements in operating mechanism for opening and closing doors and the like.

The principal object of the invention is the provision of operating mechanism for doors such as swinging doors and is characterized by means operable to open or close a door or to close or open said door whichever may be desirable. While the invention is described in connection with swinging doors, it will be understood that the mechanism is adapted for sliding and other doors or closures.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is an elevational sectional view through an operating mechanism embodying the novel features of the invention;

Figs. 2, 3 and 4 are sectional views on the lines 2—2, 3—3 and 4—4 respectively of Fig. 1; and

Fig. 5 is an elevational view at small scale showing the operating mechanism of the invention operatively connected to a door.

Referring now to the drawings more in detail, the invention will be fully described.

A casing is represented by 2 which has a base 4 secured to its lower end and a cap 6 secured to its upper end to provide an enclosed housing. The base is provided with openings 8 for receiving screws for securing the housing to a door frame 10, or the like, as shown in Fig. 5.

A tubular shaft 12 is journalled at its upper end in the cap by an anti-friction bearing 14, intermediate its ends by bearing 15 and at its lower end in a lower plate 16 secured in the casing against rotation.

A shaft 18 is disposed in the tubular shaft 12 and is oscillatable in a bearing 20 at its upper end associated with the cap 6 and a bearing 22 at its lower end associated with the base 4.

A lever 24 is fixed to the upper end of the shaft 18 by means of a key 26 and a nut 28 in threaded engagement with said shaft, all as shown.

A rod 30 is pivoted at one end to a stud 32 of

2

lever 24 and at its other end said rod is pivotally connected to a bracket 34 which is secured to a door 36, see Fig. 5. The door 36 is hinged at 38 to the door frame 10 for swinging movements between open and closed positions. As the lever 24 swings in one direction or the other the door 36 is opened or closed.

A rotor 40 is fixed to the shaft 12 and a stator 42 is fixed in the housing 2. The said rotor and stator will be of ordinary construction and co-operate to form an electric motor preferably of the slow speed type and arranged so that when energized the shaft 12 will be rotated in one direction at slow speed.

15 A coil spring 44 is provided at the upper end of the housing and has one end 46 secured to the lever 24 and its other end 48 secured to the cap 6, all as shown. The spring is arranged to swing lever 24 and rotate shaft 18 in a direction opposite to that imparted thereto by the motor.

Plates 50, 52 and 54 are disposed above plate 16 within the housing and have pins or screws 56 passing therethrough to hold them against relative shifting movements and said plates are held 20 against movement in the housing by being pressed therein or are otherwise anchored. Plate 16 is spaced above member 4.

25 A gear 58 is fixed to hollow shaft 12 and is disposed in a bore 60 of plate 52. A gear 62 has a shaft 64 journalled in plates 50 and 54 and 16, and is disposed in a bore 66 of plate 52 and is in mesh with gear 58. Portholes 109 and 110 are provided in plate 52 for the passage of liquid from and to the gears.

30 35 Plate 16, see Fig. 2, is provided with openings 68 and 70. Plate 54 is provided with openings 74 and 108 as shown in Fig. 3.

The pump and motor system is filled with oil. A driven member 89 disposed in the space 76 40 is fixed to shaft 18 by a key 82 or the like.

Within member 89 are two transverse bores 86 and 87 which carry plungers 84 and 85 cushioned by spring 88 and 89 and are held and adjusted by screws 90 and 91.

45 An abutment member 101 is attached to plate 16 by screws 97, see Fig. 2. Within it is an opening 107. A plunger 99 with a disc type head is 50 slidable in 101 and has a groove 105. Under the head of plunger 99 is a packing 98. Disposed at an angle to bore of the plunger is a plunger 104, which is pressed in groove 105 by a spring 103 backed up by adjusting screw 102. This acts as a brake on plunger 99 to prevent it from slipping out of place.

55 Plunger 99 may be installed as shown or with

head on opposite side of abutment member 101 if it is desired to have pressure applied in reverse direction.

As the motor is energized so that shaft 12 is rotated, gears 58 and 62 draw oil through openings 68 in plate 16, 108 in plate 54 and porthole 109 in plate 52 and force it out through porthole 110 in plate 52, openings 74 in plate 54 and opening 70 in plate 16 to the space between abutment 101 and movable member 89, causing member 80 to rotate thereby rotating shaft 18 and swinging lever 24 in one direction or with plunger 99 in opposite position and motor turning in opposite direction oil is drawn through openings 70 in plate 16, 74 in plate 54 and porthole 110 in plate 52 and forced out through porthole 109 in plate 52, openings 108 in plate 54 and 68 in plate 16 to space between abutment 101 and movable member 80, causing member 80 to rotate in opposite direction to open or close door 36. When member 80 is rotated so as to partially close opening 68 or 70, this restriction slows down travel, then plunger 84 or 85 contacts plunger 99 and pushes it open at end of stroke. This allows oil to flow through openings 107 from behind member 89 to forward side as spring returns it to starting position. As member 80 reaches end of return stroke plunger 85 or 84 pushes plunger 99 closed so packing 68 is pressed over openings 107 and it is ready for next operation.

The motor on rotation brings about movement of member 80 and shaft 12 so as to swing lever 24 in one direction for opening or closing the door and when the door is opened or closed, movement of the member 80 is arrested and spring 44 swings lever 24 in an opposite direction to close or open the door.

The motor may be energized in any suitable manner such as connections 92 extending therefrom to a power line 94 with a control switch 96 to open and close the circuit to the motor.

In some cases it will be desirable to arrange the apparatus so that the motor is energized for closing the door while it is opened by the spring 44. In other cases it may be desirable to bring about opening of the door by energizing the motor and closing it by action of the spring.

This mechanism permits operation of door manually at any time. In case the cycle has not been complete, the plunger 99 in abutment 101 will be open and the liquid is free to flow in either direction when pressure on the door moves member 80. In case the cycle has been completed and the plunger 99 has been pressed over the openings 107, movement of member 80 by pressure on door will force the liquid through openings 107 against the back of the disc type head on the plunger 99 and push it open.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. Coupling construction for the hollow motor shaft of a door swinging apparatus having a

driven shaft oscillatable in said motor shaft which is urged in a certain direction by a spring comprising in combination, a housing having a lower circular bore concentrically disposed relative to the longitudinal axes of said shafts, a lower cap closing the lower end of said bore and a first plate spaced upwardly therefrom and cooperating therewith to provide a closed lower chamber into which said driven shaft extends, a driven member in said chamber having a hub fixed to said driven shaft and a part extending from said hub to the side of said chamber, an abutment in said chamber fixed to said first plate extending between said hub and side of said chamber, superposed second and third and fourth plates transversely of said bore above said first plate and secured thereto, said third plate provided with adjacent bores, a driving gear in one of said bores fixed to said motor shaft and a gear in the other of said bores in mesh with said driving gear, said third plate provided with separate ports at opposite sides of and between said gears, said first and second plates provided with communicating openings therethrough providing separate fluid passageways extending from said ports to said lower chamber at opposite sides of said abutment, all adapted whereby as said motor shaft is rotated in one direction said gears displace fluid through one of said ports and passageways into said lower chamber at one side of said driven member to oscillate said member and driven shaft in one direction and opposite to said certain direction and arranged so that said driven member displaces fluid in said chamber upwardly through the other passageway and port to said gears.

2. Coupling construction for the hollow motor shaft of a door swinging apparatus having a driven shaft oscillatable in said motor shaft which is urged in a certain direction by a spring comprising in combination, a housing having a lower circular bore concentrically disposed relative to the longitudinal axes of said shafts, a lower cap closing the lower end of said bore and a first plate spaced upwardly therefrom and cooperating therewith to provide a closed lower chamber into which said driven shaft extends, a driven member in said chamber having a hub fixed to said driven shaft and a part extending from said hub to the side of said chamber, an abutment in said chamber fixed to said first plate extending between said hub and side of said chamber, superposed second and third and fourth plates transversely of said bore above said first plate and secured thereto, said third plate provided with adjacent bores, a driving gear in one of said bores fixed to said motor shaft and a gear in the other of said bores in mesh with said driving gear, said third plate provided with separate ports at opposite sides of and between said gears, said first and second plates provided with communicating openings therethrough providing separate fluid passageways extending from said ports to said lower chamber at opposite sides of said abutment, all adapted whereby as said motor shaft is rotated in one direction said gears displace fluid through one of said ports and passageways into said lower chamber at one side of said driven member to oscillate said member and driven shaft in one direction and opposite to said certain direction and arranged so that said driven member displaces fluid in said chamber upwardly through the other passageway and port to said gears, said abutment provided with an opening therethrough for the flow of fluid

displaced by said driven member, a valve for closing said opening, and means on said driven member for engaging and moving said valve to open position as said driven member approaches the end of its movement in said one direction.

3. Coupling construction for the hollow motor shaft of a door swinging apparatus having a driven shaft oscillatable in the motor shaft comprising in combination, a housing having a lower circular bore concentrically disposed relative to the longitudinal axes of the shafts, a lower cap closing the lower end of the bore, a first plate spaced upwardly from said lower cap and cooperating therewith to provide a closed lower chamber into which the driven shaft extends, a driven member in the chamber having a hub fixed to the driven shaft, an abutment in the chamber fixed to said first plate extending between said hub and the side of the chamber, superposed second and third and fourth plates transversely of the bore above said first plate and secured thereto, said third plate being provided with adjacent bores, a driving gear in one of the bores fixed to the motor shaft, a gear in the other of the bores in mesh with said driving gear, said third plate being provided with separate ports at opposite sides of and between said gears, said first and second plates being provided with communicating openings therethrough providing

separate fluid passageways extending from the ports to the lower chamber at opposite sides of said abutment, all adapted whereby as the motor shaft is rotated in one direction said gears displace fluid through one of the ports and passageways into the lower chamber at one side of said driven member to oscillate said driven member and driven shaft in one direction and opposite to the said certain direction and arranged so that said driven member displaces fluid in the chamber upwardly through the other passageway and port to said gears.
